VACUUM CLEANER

Robert A. Ponselle, New York, N. Y.

Application July 27, 1940, Serial No. 348,142

4 Claims. (Cl. 183—37)

This invention relates to vacuum cleaners of the mobile type and is concerned more particularly with a vacuum cleaner having numerous novel features of construction which give it a wide range utility, increase its efficiency, and cause it to operate with much less noise than prior machines of like capacity. The cleaner of the invention is especially suitable for heavy duty commercial and industrial work, since it may be employed for removal of dust, liquid, suds, rubbish, metal waste and chips, etc., by vacuum action and also as a blower for cleaning, spraying, and similar purposes. Despite its high capacity, it is of simple compact construction and relatively light in weight so that it may be readily moved about as desired and may be employed in restricted spaces.

Portable vacuum cleaners as heretofore constructed have been of two general types, those having a bag or filter within a housing and those having an external bag, and neither type is satisfactory for cleaning operations which involve removal of both dry and wet materials. The internal bag type of machine cannot be used for removal of liquids, suds, etc., because the bag within the housing would at once become wet, and if the machine were then used for dry dust removal, the particles of dust would adhere to the bag and ultimately clog the openings therethrough so that the air flow would be cut down and the efficiency of the machine reduced. The prior external bag machines intended for dual purpose cleaning include a tank into which the incoming air stream is admitted and in which it is intended that the liquid will collect, and the stream leaving the tank then passes through the fan and into the bag. However, the velocity of the stream entering the tank is so high that splashing of the liquid occurs therein and a mist is formed which passes into the bag and moistens it. Here again, if the machine with the bag thus moistened is used for the removal of dry dust, the bag will become clogged and the efficiency reduced. Accordingly, the external bag machines are provided with two bags to be used alternately for wet and dry cleaning. Aside from that, such machines are bulky and cumbersome because of the large bag mounted outside the tank.

The new cleaner is of the internal bag type but is so constructed that it may be used for removal of both wet and dry materials without changing of the bag and without danger of the bag becoming clogged and the operating efficiency of the apparatus reduced. The new machine includes a housing containing a motor and fan unit

5 which operates to draw air into the housing through an inlet and expel it through an outlet. Inside the casing between the inlet and unit is a filter, and the air from which the solid materials have been removed by the filter passes first through the motor and then to the fan so that the maximum cooling effect for the motor is obtained. The motor and fan unit is preferably suspended on a mounting from a cover for the housing so that the cover and unit may be removed as one, and the mounting is resilient and thus prevents transmission of vibration from the moving parts to the rest of the machine. Adjacent the housing inlet is a device for reducing the 10 velocity of the incoming air so that liquids and suds are removed from the air stream and deposited without splashing in the bottom of the housing. The provision of such a device, accordingly, makes possible the use of an enclosed filter even though the machine is to be used for removal of liquids and suds, since the device avoids the possibility of liquids and suds splashing on the filter. With the filter enclosed, only filtered air passes through the motor and fan unit, so that 15 any liability of those parts being injured by airborne material is eliminated.

The cleaner includes various new features additional to those mentioned and for a better understanding of the invention, reference may be 20 had to the accompanying drawing in which

Fig. 1 is a view partly in elevation and partly in section of one form of the new apparatus; and Fig. 2 is a sectional view of a detail.

The cleaner illustrated includes a rolling carriage comprising a platform 10 supported on wheels 11 and a caster 12. The wheels are mounted for rotation relative to the carriage in any suitable manner and the caster has a shank received in a bore in an extension 13 from the platform. Resting on the top of the platform is a container 14 which is of suitable capacity and is preferably made of sheet metal. In normal use, the container is secured in place on the platform and for this purpose, the platform is provided 25 with a pair of fixed stops 15, of which only one is illustrated. These stops may be blocks of rubber mounted in the brackets 16 in which the axles of the wheel 11 are secured and the container is held against the stops by means of an endwise movable rod 17 mounted in an opening in the wall of the extension 13 and having a block of cushioning material 18 on its end.

The rear end of the rod 17 is connected by a link 19 to the lower end of a plunger 20 mounted in the extension for vertical movement and hav-

ing an enlarged upper end 21. The link is secured to the rod 17 by a slot and pin connection and a spring 22 encircles the rod and bears at one end against the inner surface of the extension and at the other against the end of the link. The construction of the parts described is such that when the plunger is in the fully depressed position illustrated, the rod 17 is moved inwardly so that the block 18 bears against the container and forces it into firm contact with the stops 15 against the force of the springs 22. When the container is to be removed, the plunger is raised and the link pulls back upon the rod 17 and disengages block 18 from the side of the container, the spring then acting through the link to hold the plunger raised.

Mounted on the upper end of the container is an adapter 23, which is preferably made of suitable sheet metal and is secured in place by clamps (not shown) which are mounted on the container near its upper edge and have portions overhanging the peripheral flange 24 at the lower end of the adapter. The upper end of the adapter has an opening closed by a cover consisting of a sleeve 25^a and a dome 25^b and this cover is held in place by clamps (not shown) secured on the adapter and having portions overhanging the peripheral flange 26 on the sleeve. The adapter has a lower end which may be of varying diameters depending on that of the container used and, in some machines, no adapter is used and the cover is secured directly to the container. The container, with or without the adapter, constitutes a housing having a top opening closed by the cover, and attached to the cover and extending downward into the adapter or container is a motor and fan unit. By releasing the clamps securing the cover in place, the cover and the motor and fan unit can be removed as one, whereupon the filter bag to be described is accessible and can be shaken to remove adhering dust.

Air is drawn into the container through an opening in the wall. Surrounding the opening is a plate 28 secured to the outer wall of the container and having a short integral sleeve 28^a extending through the opening, a gasket 28^b being placed between the plate and wall to prevent leakage into the container around the sleeve. The plate has an outwardly projecting sleeve 29 and a tube 30 inserted into sleeve 28^a extends inwardly into the container and is enclosed by a casing 31 secured to the inner wall of the container. The casing and tube are eccentric with the tube lying near the upper side of the casing and the casing has an end wall 32 which lies spaced from the inner end of the tube. The wall 32 is integral with a portion 33 of the side wall of the casing and these parts form an end member pivoted at 34 on a bracket secured to the remainder of the casing. A spring 35, encircling the pivot, tends to hold the end member in closed position and the member is preferably secured in place by a catch which may consist of a loop 36 pivoted on the wall of the casing and receivable into a notch in a projection 37 secured to the side wall member 33. The casing has a discharge opening 38 in the lower portion of its side wall near the wall of the container and, as shown, the opening has a cross-sectional area substantially greater than that of the tube 30.

When the machine is operating, air enters the inlet at a high velocity, such as 90 M. P. H., and the air stream strikes the end wall 32 of the casing and then rebounds and rushes back and

strikes the container wall and again rebounds. The air streams rebounding from the two walls collide and mingle to flow out laterally through the discharge opening and the result of such action is that the air flow through the opening into the main space within the container is at a greatly reduced velocity, as, for example, 10 to 12 M. P. H. The air then passes upward in the container, while the air-borne material, such as liquids, suds, the heavier particles of dust, chips, etc., drop out of the air stream and collect in the bottom of the container. Since the velocity of the stream issuing from the casing is relatively low, the liquids and suds are deposited without splashing and no mist is created to be carried along by the stream flowing upward in the container.

The casing with the tube 30, accordingly, constitutes a device which effectively reduces the velocity of the air stream entering the container and permits separation of the air and air-borne material so that the latter is not carried along to the filter bag. The space within the casing around the tube 30 is of a cross-sectional area substantially greater than that of the tube and the device thus offers no obstruction to the flow of air therethrough and acts to diffuse the stream. The action of the air stream within the casing normally prevents the latter from becoming clogged but, if dry dust is carried into the machine when the interior of the casing is wet, some of the particles may adhere to the casing walls and the movable end member is provided so that the interior of the casing may be cleaned out when necessary. The spring on the end member insures that the latter will be closed automatically.

The flow of air is produced by a motor driven fan unit which comprises an enclosure 39 suspended from the cover on a sleeve 40 of flexible resilient material, such as rubber. The upper end of the sleeve is clamped to the cover in any suitable manner and the lower end is clamped to the upper end of the enclosure 39. Because of the flexibility of the sleeve, the vibration of the moving parts is kept from being transmitted to the cover and this lessens the noise of operation. The enclosure has an air inlet at its lower end and a motor 41 is secured to the lower end of the enclosure in line with the inlet. The motor is of conventional type and has openings 42 at its lower end so that all the air drawn into the container flows upward through the motor before reaching the fans. This insures the maximum cooling effect for the motor so that it may be operated at a high output rate without overheating.

The motor is provided with a shaft 43 mounted in a bearing 44 at the lower end of the motor casing and another bearing 45 at the upper end of the enclosure. Mounted on the shaft in spaced relation are one or more fans 46 of usual construction, diffusers 47 being provided when more than one fan is used. The air leaving the fans passes out of the enclosure through outlet openings 48 and enters the dome of the cover.

A baffle 49 of sound insulating material lies within the dome of the cover above the enclosure outlets and may conveniently comprise a plate having covered on at least one face and preferably on both with a heavy layer 50 of felt. The baffle is suspended on bolts 51 from the top of the cover and the bolts are provided with spacing sleeves to hold the baffle in proper position. The top of the cover is provided with a lining 52 of

sound insulating material, such as felt, and the dimensions of the parts are such that a narrow channel 53 of a total cross-sectional area at least equal to that of the container inlet is provided for the escape of the air between the edge of the baffle and the inner surface of the lining. At its top, the cover has an air outlet opening which is surrounded by a plate 54 secured to the outer surface of the cover and provided with a sleeve 55 aligned with the opening.

Interposed between the housing inlet and the motor is a filter 56 which may conveniently take the form of a bag of suitable fabric having a stiffening disc 56^a of fibre secured to its lower end. The bag is provided with a stiffening ring 56^b along its upper edge and is supported by a metal ring 57 having a downwardly curved portion into which the upper edge of the bag with ring 56^b therein can be sprung in place. The ring 57 has an outwardly extending flange embedded in a rubber ring 57^a and the rubber ring is adapted to rest upon the upper end of the adapter 23 or the container, when no adapter is used, and be clamped in place by the flange 26 of the sleeve 25 of the cover. In order that the bag may not be drawn upward when the machine is operating, the fan enclosure is provided with a frame 58 of wire or similar material which extends down into the bottom of the bag. The stiffening disc 56^a prevents the bottom of the bag from being sucked up against the inlets 42. The frame is of such construction as not to cut down air flow through the bag, and, since it is attached to the fan enclosure, removal of the cover with the motor and fan unit also removes the frame, so that the bag can be shaken to free dust particles adhering thereto. Such shaking is done while the bag is in place, so that the dust is not released into the atmosphere, and when the bag is to be removed for any purpose, its ring 56^b is sprung out of ring 57 with an upward movement.

The vacuum produced by the action of the fan is applied to the surface to be cleaned through a hose 59 connected to the usual handle having a tool at one end. The hose is formed of a metal end piece 60 which is insertable in the sleeve 29 and the end piece has a beveled end surface 61 and is formed with a recess 62 rearwardly thereof, which may be either of small dimensions or extend circumferentially of the end piece. A lever 63 is pivotally mounted on the sleeve 29 and is acted on by a compression spring 64, the lever having an end to which is pivoted a pin 64^a which passes through an opening in the sleeve and enters the recess 62. With this arrangement, the end piece may be inserted in the sleeve and the beveled end, engaging the pin on the lever, pushes the pin upward and swings the lever against the spring so that the end piece can be inserted until the end of the pin snaps down into the recess 62. Thereafter, the end piece is securely held in the sleeve and can be removed only by swinging of the lever against its spring to move the pin on the lever out of the recess. The sleeve 55 at the outlet of the machine is also provided with a spring-pressed lever similar to lever 63 in order that the end of a hose may be secured in the sleeve when the machine is used for blowing or spraying.

The connection described, consisting of a sleeve carrying a lever and an end piece insertable in the sleeve and provided with a recess, may be used for connecting the hose to the handle of the tool and the tool head to its handle. Whenever a rigid connection is used, the recess in the end

piece is of small dimensions but if a swivel connection is desired, a circumferential recess is used.

The machine is provided with a handle 65 secured to the carriage and the operation of the motor is controlled by a switch 66 mounted within the cover near the upper end thereof and having a trigger 67 exposed at the top of the cover. The motor supply cable 68 leads into the switch through an opening in the cover and a cable 69 leads from the switch to the motor terminals.

The new machine is quiet in operation because the motor and fan are enclosed and so mounted that vibration therefrom is not transmitted to the rest of the machine and the air passing from the motor to the outlet flows through a passage defined by sound insulating material. The baffle also deadens the sound of the outgoing air by breaking up the air stream.

By the provision of the device for reducing the velocity of the incoming air, the machine, although equipped with an internal filter, may be used for removal of liquids and suds, since the device so reduces the velocity of the stream that the liquids and suds are deposited without splashing and wetting of the filter is prevented. The use of the internal filter reduces the overall bulk of the machine and makes its use possible in restricted spaces, and the construction is such that the filter can be easily cleaned and removed and replaced and the container can be easily emptied.

The mounting of the motor and fan unit on the cover makes it possible to remove the cover and unit as one so that the fan is readily accessible and the moving parts can be readily reached for repair and maintenance. The provision of bearings for the motor shaft at one end of the motor housing and at a point beyond the fan keeps the shaft from whipping with resultant injury to the fan and both bearings are readily accessible for lubrication.

As pointed out above, the new machine is suitable for a wide variety of cleaning purposes and may be used alternately for removal of wet and dry materials without the necessity of changing the filter bag. It is highly effective in removing liquids from floors which have been scrubbed and carpets which have been cleaned and are covered with soap suds. In addition, it has been successfully used for removal of liquids from flooded areas.

I claim:

1. In a vacuum cleaner comprising a container having an air inlet and means for creating a partial vacuum within the container; a device within the container through which air passes from the inlet into the container, said device comprising a tube extending into the container as a continuation of the inlet, a casing enclosing the tube and having a normally closed end spaced from and opposite the inner end of the tube but relatively close thereto, the other end of the casing being closed by a wall substantially parallel to said normally closed end, said casing having a discharge outlet in a lateral wall thereof.

2. In a vacuum cleaner comprising a container having an air inlet and means for creating a partial vacuum within the container; a device within the container through which air passes from the inlet into the container, said device comprising a tube extending into the container as a continuation of the inlet, a casing enclosing the tube and having a normally closed end spaced from and opposite the inner end of the tube, the

other end of the casing being closed by a wall substantially parallel to said normally closed end, said casing having a discharge outlet in a lateral wall thereof.

3. In a vacuum cleaner comprising a container having an inlet and an outlet and a motor driven fan for drawing air through the inlet and causing it to be expelled through the outlet; means interposed in the path of the air stream entering the container for reducing the velocity of the incoming air and for diffusing said air before it enters the main portion of the space within said container, said means including a tube extending inwardly from the inlet and a casing mounted eccentrically of the tube and enclosing the latter, said casing having a movable end portion normally closing the inner end of the casing and spaced from and opposite the inner end of the tube, said casing also having a discharge port in its side wall remote from the inner end of the tube.

4. In a vacuum cleaner comprising a container having an inlet and an outlet and a motor driven fan for drawing air through the inlet and causing it to be expelled through the outlet; means interposed in the path of the air stream entering the container for reducing the velocity of the incoming air and for diffusing said air before it enters the main portion of the space within said container, said means including a tube extending inwardly from the inlet and a casing enclosing the tube and having a closed end spaced from and opposite the inner end of said tube, said casing also having a wall substantially parallel to said closed end so that the incoming air will impinge against said closed end and rebound against said substantially parallel wall and from it rebound back against the oncoming stream, said casing having a lateral discharge adjacent the inlet.

ROBERT A. PONSELLE.
